UNITED STATES PATENT OFFICE.

PAUL BOWERS, OF STARBUCK, WASHINGTON.

ARCH-TUBE SAFETY DEVICE.

1,105,397.

Specification of Letters Patent. Patented July 28, 1914.

Application filed February 9, 1914. Serial No. 817,646.

To all whom it may concern:

Be it known that I, PAUL BOWERS, a citizen of the United States, residing at Starbuck, in the county of Columbia and State of Washington, have invented new and useful Improvements in Arch-Tube Safety Devices, of which the following is a specification.

This invention relates to boilers of that type wherein water tubes extend across the fire-box above the grate and which tubes are generally known as arch tubes. These tubes are subjected to the most intense heat and accidents frequently occur by reason of the fact that the arch tubes burst, causing damage of various kinds necessarily resulting from release of water and steam into the fire-box.

It is one of the objects of my invention to provide means, preferably acting automatically, for closing ingress to the arch tubes when internal pressure therein is lowered with respect to boiler pressure by reason of breakage or cracking of the arch tubes so as to cut such broken or cracked tube out of service.

Other features and objects of the invention will be more fully described in connection with the accompanying drawings, and will be more particularly pointed out and ascertained in and by the appended claims.

In the drawings: Figure 1 is a longitudinal vertical sectional view of a locomotive boiler, showing one application of the device of my invention thereto. Fig. 2 is an enlarged sectional contracted view of portions of the boiler and fire-box, showing an arch tube in service. Fig. 3 is a view similar to Fig. 2, showing the position of the device of my invention when the tube is cut out of service. Fig. 4 is a sectional view of the device of my invention detached from the boiler.

Like characters of reference designate similar parts throughout the different figures of the drawings.

I have illustrated the device of my invention as applied to a locomotive boiler and to the arch tubes thereof, but I would have it understood that my invention is not limited to this particular utility.

In the drawings, 1 designates the fire-box and 2 the boiler, the fire-box vertical walls being indicated at 3 and 4 and those portions of the boiler shell to which refer-

ence will be made, being indicated at 5 and 6.

A plurality of tubes, one only being shown and indicated at 7, extends from walls 3 to 4 in arched form to support firebrick 8 and 60 the tube 7 communicates with the boiler at a relatively low point, at its forward end, and at a relatively high point at its rearward end, thereby causing a flow through the tube in the direction of the arrow, when 65 the tube is in service. Breakage of the tube, as indicated at 9, would cause the steam and water to rush into the fire-box and force the door in a manner to do the usual damage resulting from such breakage. 70

In accordance with the most improved form of my invention, I provide devices at each end of the tube 7, which are responsive to lowering of the pressure in the tube to close ingress thereto from the boiler when 75 pressure in the tube decreases with respect to the pressure in the boiler.

As illustrated more particularly in Figs. 2 and 3, 10 designates a valve closure of the truncated conical type, which is adapted to 80 seat against the reamed terminal 11 of the tube 7. As the devices at both ends of the tube are similar in construction and operation, a description of one will suffice. In order to increase the area of the closure 10, 85 which is responsive to boiler pressure, I provide the same with a head 12 against the face 13 of which flow from the boiler is effective to effect closing action, it being understood that the main area will be the back 90 of the closure, which is indicated at 14. The closure 10 is provided with a stem 15, which is preferably exteriorly threaded to receive a nut 16, the adjustment of which regulates the extent of opening movement 95 of the closure 10, in a manner which will presently appear. The stem 15 is provided with a reduced guiding portion 17, which is preferably exteriorly threaded to receive a 100 nut 18. A guide for the closure 10 is provided in the form of a rectangular frame 19 through one wall of which, as indicated at 20, the stem 17 is slidably mounted, so that the closure 10 will be held to a straight line of movement axially of its stem. In order to 105 retain the closure 10 in a normal open position, I interpose a relatively weak spring 21 between the nut 18 and the frame portion 20, opening movement of the closure being limited by abutment of the nut 16 against 110

the part 20 of the closure guide 19. The closure guide 19 is provided with a threaded stud 22, which is turned into a plug 23 in the shell wall 6. The plug 23 is shown 5 threaded in the wall 6, and the threaded engagement of the stud 22 affords a relatively extensive range of initial adjustment of the closure 10 with respect to the seat of the tube 7. It will now be clear that if 10 any one of the arch tubes 7 became broken or cracked so that interior pressure therein was less than boiler pressure, the water and steam seeking admission to such broken tube would instantly and automatically seat the 15 closures 10 at both ends of such tube, thereby cutting the tube out of service so that little or no leakage would result. Furthermore, boiler pressure would retain the closure seated so as to most effectively cut such 20 tube out of service until it could be removed.

It will be seen that installation of the device of my invention requires a minimum expense, and as the closures are normally inactive and only become active responsive to 25 boiler pressure, their certainty of action is not dependent upon springs or other mechanism and therefore they can be relied upon to effectively perform their function until 30 repairs can be made.

While I have herein shown and described one specific form of my invention, I do not wish to be limited thereto except for such 35 limitations as the claims may import.

I claim:

1. In combination, a boiler provided with a fire-box, a tube extending across the fire-box and communicating at its ends with the

interior of the boiler, and a valve device at each end of the tube responsive to boiler pressure for automatically and simultaneously closing ingress to both ends of the tube from the boiler when pressure in the former decreases with respect to pressure in the latter, substantially as described. 40

2. In combination, a boiler provided with 45 a fire-box, a tube extending across the fire-box and communicating at its ends with the interior of the boiler, a valve device responsive to boiler pressure for automatically closing each end of the tube against ingress 50 thereto from the boiler, and springs for normally holding said valve devices in open positions, substantially as described.

3. In combination, a boiler provided with 55 a fire-box, a tube extending across the fire-box and having its ends projecting into the boiler, and a valve closure structure for each end of the tube each comprising a closure having a stem, an adjustable abutment nut on the stem, a guide frame adjustably mounted on the boiler and having guiding engagement with said stem, and a spring coacting with the stem and the guide frame to normally hold the valve closure away from the tube end, substantially as described. 60

In testimony that I claim the foregoing as my own, I hereby affix my signature in the presence of two subscribing witnesses.

PAUL BOWERS.
